CLAIM

The ornamental design for a women's garment, substantially as shown and described.

DESCRIPTION

FIG. 1 is a top perspective view of a first embodiment of a women's garment showing our new design with environment;

FIG. 2 is a left side elevation view of the women's garment of FIG. 1, shown with environment omitted;

FIG. 3 is a right side elevation view thereof;

FIG. 4 is a front elevation view thereof;

FIG. 5 is at rear elevation view thereof;

FIG. 6 is a top plan view thereof;

FIG. 7 is a bottom plan view thereof;

FIG. 8 is a top perspective view of a second embodiment of a women's garment showing our new design with environment;

FIG. 9 is a left side elevation view of the women's garment of FIG. 8, shown with environment omitted;

FIG. 10 is a right side elevation view thereof;

FIG. 11 is a front elevation view thereof;

FIG. 12 is at rear elevation view thereof;

FIG. 13 is a top plan view thereof; and,

FIG. 14 is a bottom plan view thereof.
